United States Patent Office

Des. 195,517
Patented June 25, 1963

195,517

CABINET OR SIMILAR ARTICLE

Robert R. Peters, Great Neck Estates, N.Y., assignor to
Patents Management Corporation, Atlanta, Ga., a cor-
poration of Georgia

Filed May 10, 1960, Ser. No. 60,521

Term of patent 14 years

(Cl. D33—19)

FIG.1

FIG.5

FIG.6

FIG.4

FIG.2

FIG.3

FIG. 1 is a perspective view of a cabinet or similar article showing my new design.

FIG. 2 is a side view thereof.

FIG. 3 is a rear view thereof.

FIG. 4 is a top view thereof.

FIG. 5 is a sectional view on a reduced scale of the cabinet shown in FIG. 1 taken along lines 5—5 of FIG. 1.

FIG. 6 is a sectional view on a reduced scale of the cabinet shown in FIG. 1 taken along lines 6—6 of FIG. 1.

The sides of the cabinet not shown have an appearance substantially similar to the sides of the cabinet shown.

I claim:

The ornamental design for a cabinet or similar article, as shown and described.
